UNITED STATES PATENT OFFICE.

ALPHONSE W. ZIEGLER, OF NEW YORK, N. Y.

DESIGN FOR A CORN-HOLDER.

SPECIFICATION forming part of Design No. 25,793, dated July 21, 1896.

Application filed August 10, 1895. Serial No. 558,938. Term of patent 3½ years.

To all whom it may concern:

Be it known that I, ALPHONSE W. ZIEGLER, a citizen of the United States, residing at New York, in the county and State of New York, have invented and produced a new Design for Corn-Holders, of which the following is a specification, reference being had to the accompanying drawing, forming part thereof, in which the figure shows an elevation of a corn-holder.

The leading feature of my design consists in the handle A, which is segmental or curved at its upper end, as shown at B, the end being flared or enlarged, the lower end of said handle being curved outwardly and downwardly, as shown at C, from whence it is carried directly downward and curved or bent upon itself at D, from whence it is again carried upwardly and curved inwardly at E, from whence it is wound around the main portion

of the handle forming a substantially rectangular extremity.

It will be observed that my new and original design is symmetrical in shape and pleasing in configuration, and the essential features are the segmental or curved arm and the handle portion, the extremity of which is wound around the lower portion of the arm.

What I claim is—

The design for a corn-holder as herein shown and described.

In testimony that I claim the foregoing as my invention I have signed my name, in presence of the subscribing witnesses, this 6th day of August, 1895.

ALPHONSE W. ZIEGLER.

Witnesses:

L. M. MULLER,
S. L. HAWKSHURST.
